UNITED STATES PATENT OFFICE.

ALBERT W. MEYER, OF TERRE HAUTE, INDIANA.

COMPARTMENT-URN.

SPECIFICATION forming part of Letters Patent No. 574,927, dated January 12, 1897.

Application filed March 11, 1896. Serial No. 582,799. (No model.)

To all whom it may concern:

Be it known that I, ALBERT W. MEYER, a citizen of the United States, residing at Terre Haute, in the county of Vigo, State of Indiana, have invented certain new and useful Improvements in Compartment-Urns, of which the following is a specification, reference being had therein to the accompanying drawings.

This invention relates to certain new and useful improvements in compartment-urns; and it has for its objects, among others, to provide a compartment-urn in which a coil shall extend from the steam-chamber into the water-compartment, thus assisting in heating the water; also, to extend said water-compartment downward, so as to bring the hot air from the gas or other burner in direct contact with the bottom thereof, so as to boil the water when desired. I provide a direct connection with the water-main extending into this water-compartment, while for drawing off the hot water I provide a pipe extending under the perforated stand and out through the opposite side of the inclosing case. The jacket is mounted so that it may be elevated when desired and held in the elevated position by springs or counterbalance-weights or equivalent means. I provide improved means for holding the sack detachably in position, and I also provide a novel device for holding a drip-cup under the faucet.

Other objects and advantages of the invention will hereinafter appear, and the novel features thereof will be particularly pointed out in the appended claims.

The invention is clearly illustrated in the accompanying drawings, which, with the letters of reference marked thereon, form a part of the specification, and in which—

Figure 1 is a substantially central vertical section through an urn embodying my present improvements. Fig. 2 is a perspective view of the receptacle-holder removed. Fig. 3 is a top plan of the jacket. Fig. 4 is a perspective view of one of the sacks and its holder, and Fig. 5 is a perspective view of the drip-cup holder removed.

Like letters of reference indicate like parts throughout the several views.

Referring now to the details of the drawings by letter, A designates the base portion

or stand, which may be as ornamental in appearance as may be desired and of suitable material, being provided with a horizontal supporting flange or shoulder a, extending 55 inward, as seen in Figs. 1 and 3, and a surrounding vertical flange a', as shown in the same views, and upon this shoulder a and within this flange a' is designed to be supported the outer jacket B. This base or stand is provided with a bottom A', forming the chamber or compartment A², designed to contain water, and this bottom has the triangular opening A³ therein, as seen best in Fig. 3, through which extends the lower end of the 65 water-compartment C, so that its bottom c will be substantially on a line with the bottom A', as seen in Fig. 1, so that the same may be brought in direct contact with the heat from the gas or other means employed 70 for heating the contents of the urn. The compartment A² is provided with an overflow-pipe a², extending above the normal water-line x in said compartment, as seen in Fig. 1.

B is the outer casing or inclosing jacket, 75 the lower end of which is designed to fit within the flange a' of the base and to rest upon the shoulder or ledge a thereof, in which position it is shown in Fig. 1. It is provided with suitable slots c', as shown in Fig. 1, to allow 80 it to slip over the pipes and faucets extending from the compartments, which are inclosed within the casing or outer jacket. This casing or jacket is provided with a suitable top C', removably supported thereon and 85 which may be as ornamental in appearance as may be required. The jacket is designed to be removed or elevated so as to permit of access to any parts inclosed therewithin, and in this instance I have shown the same as 90 having the radial arms D, which are designed to be guided by the posts or uprights E, which may be or may not be secured to the base, preferably, however, being held in suitable lugs a³ at the bottom thereof, (see Fig. 3,) and 95 in order to hold the jacket in its elevated position or positions any suitable means may be provided, such, for instance, as cords or chains F, secured to the upper arms D, said chains or cords passing over pulleys f, located within 100 the upper ends of the uprights E, which are hollow, and the other ends of the cords or

chains being connected with counterbalance-weights F' , designed to move within the up-rights, as indicated in Fig. 1, so that as the jacket is elevated the weights are caused to descend and counterbalancing the weight of the jacket hold the same in any of its ad-justed positions.

E is a skeleton frame or support comprising the bottom e , the star-shaped top e' , and the vertical partitions E' , of wire-gauze or analogous material, three of the compartments thus formed being provided with a reticulated bottom e^3 , while the fourth is without bottom, as seen in Fig. 1, and through the space thus left is adapted to pass the water-compartment, as indicated in said Fig. 1. The bottom ring e has the upwardly-extending flanges e^3 at the inclosed or outer edges of the triangular spaces of the skeleton frame, which serve to hold the lower ends of the compartments when the latter are placed in position. These compartments G are substantially triangular in form, with one side (the outer side) upon a curve conforming to the curvature of the outer jacket or casing, and these compartments are provided with suitable faucets g , as indicated, through which their contents may be withdrawn when desired, and these faucets project through slots or openings in the outer or inclosing jacket. One of these may contain coffee, one milk, another chocolate, or any other desired liquid. They may each be provided with a suitable cover, while the water-compartment C is provided with a suitable top c^3 and a filling-aperture inclosed by a suitable cap or cover c^4 , as seen in Figs. 1 and 2. The water-compartment is provided with a flange C^2 upon its outer wall, adapted to rest upon the ledge a of the casing, as seen in Fig. 1.

I is the sack for holding the coffee, and this is held in a suitable holder adapted to be retained over the upper end of the compartment in which it is placed, and the construction of this holder is best seen in Fig. 4, wherein I' is a substantially triangular frame with one side on a curve conforming to the contour of the outer wall of the compartment and the inclosing jacket, and this frame, which is preferably of metal, is provided with the horizontal surrounding flange i and the vertical flange i' , which latter is provided with hooks or pins i^2 .

J is a band adapted to fit over the vertical flange i' of the frame.

In practice the bag is inserted through the opening in the frame I' and its upper edge turned over the upper edge of the said vertical flange, being forced over the pins i^2 , and then the band J is forced down over the flange I' and the portion of the sack which is turned thereover, and, as the band is forced down, the turned-over edge of the bag or sack is likewise drawn down, and the band, passing over the pins forced down onto the flange i , securely locks the upper end of the sack in

position, and the flange i resting on the upper edge of the compartment G the sack is supported in position. The sack may be readily removed by forcing off the band.

K is a steam-pipe leading from the steam-chamber A^4 and having at its upper end a connection with the pipe K' , which may convey steam to a steam cooker or heater, and connected with this pipe is a lateral pipe k , which connects with the depending pipe k' , extending into the hot-water compartment C and terminating in a coil k^2 , as clearly shown in Fig. 1, so that the steam may assist in heating the water in the said compartment.

L is a pipe connecting with the water-compartment C , and extending downward and through the compartment A^2 and thence up under the bottom of the perforated stand or skeleton frame extends out through an opening in the outer jacket or surrounding case, and is provided with a faucet L' , by which the hot water from the said compartment may be withdrawn, when desired.

M is a drip-cup adapted to be supported beneath the spigot L' , and this cup is supported by means of the holder M' (shown in enlarged detail in Fig. 5) and composed of wire, comprising the ring m , into which the cup is designed to be inserted and supported by its flange m' , while from this ring extend upwardly the converging arms m^2 , which at their upper ends connect with the lateral parallel arms m^3 , which extend upward to form the arch m^4 , at the upper end of which the wire is twisted, as at m^5 , and thence extended in a plane substantially parallel with the arms m^3 , forming the loop m^6 , thence twisted, as at m^7 , and extended downward to form the arch m^8 , thence outward, forming the parallel arms m^9 , and these extended upward to form the arch m^{10} .

In practice the handle of the spigot is received in the loop m^6 . The portion of the spigot to the rear of the handle and globular portion is embraced by the arches m^8 and m^{10} and the parallel arms m^9 , while the front portion is embraced by the arch m^4 and the vertical side arms thereof, the holder being retained upon the faucet by the spring action of the wire of which the holder is composed. It may be readily removed when desired, and the drip-cup may be removed from its supporting-ring without removal of the faucet from the holder.

Modifications in detail may be resorted to without departing from the spirit of the invention or sacrificing any of its advantages.

It will be understood that the invention is not restricted to the number of compartments. The same may be varied at will.

The urn may be used for cold drinks as well as for hot, in which case I place ice in the water-compartment C . I may sometimes employ a jacket with slots, such, for instance, as is shown in my Patent No. 504,439, dated September 5, 1893.

Having thus described my invention, what I claim as new, and desire to secure by Letters Patent, is—

1. In a compartment-urn, the combination 5 with the base having an opening in its bottom, of a skeleton frame supported above said base, the compartments within said skeleton frame, and a water-compartment extended beneath the bottom of the skeleton 10 frame; substantially as described.

2. In a compartment-urn, the combination 15 with the base having an opening in its bottom, a skeleton frame supported above said base, the compartments within said skeleton frame, and a water-compartment extended beneath the bottom of the skeleton frame, said skeleton frame having its vertical partitions and bottom formed of reticulated material; substantially as described.

20 3. In a compartment-urn, the combination with the base having an opening in its bottom, of a skeleton frame supported above said base, the compartments within said skeleton frame, and a water-compartment extended beneath the bottom of the skeleton frame, and a steam-coil within the water-compartment; substantially as described.

4. In a compartment-urn, the combination 30 with the base having an opening in its bottom, of a skeleton frame, supported above said base, the compartments within said skeleton frame, a water-compartment extended beneath the bottom of the skeleton frame, a pipe connected with the steam-chamber, and a branch pipe leading from 35 said pipe extending to and terminating in a coil within the water-compartment; substantially as described.

5. The combination with the base having 40 the vertical flange, an inwardly-extending horizontal shoulder, of the water-compartment having a horizontal flange resting on said shoulder, and an inclosing jacket held within the vertical flange and supported on 45 the shoulder of the base; substantially as described.

6. The combination with the base having hot-water compartment, and an opening, of the skeleton frame supported above the base,

the water-compartment extended through 50 the opening in the base, the inclosing jacket, the pipe leading from the water-compartment through the hot-water compartment and extended through an opening in the jacket, a steam-pipe connected with the 55 steam-chamber of the urn, and a branch leading therefrom and communicating with the coil within the water-compartment; substantially as described.

7. In a compartment-urn, a skeleton frame 60 having reticulated vertical partitions, a bottom to three compartments, the remaining compartment being bottomless, and flanges extending vertically from the bottom rim at the outer edges of the vertical partitions; and 65 a water-compartment extending into the bottomless compartment, substantially as described.

8. The combination with the sack, and the frame, having horizontal and vertical flanges, 70 of a band adapted to fit over the vertical flange to hold the sack thereon, and pins on the vertical flange for holding the turned-over edge of the sack; substantially as described.

9. The combination with a triangular frame having one side curved and formed with surrounding horizontal and vertical flange, and pins on said vertical flange, of a sack having 80 its edges turned over the vertical flange, and a band triangular in form with one side curved and fitted over the vertical flange and the turned-over edge of the sack; substantially as described.

10. In a compartment-urn, the combination 85 with a faucet, of a drip-cup holder formed of wire, and having a loop to receive the handle of the faucet, arched portions to embrace the horizontal portion of the faucet upon opposite sides of the handle, and the depending 90 arms carrying a ring to receive a drip-cup; substantially as described.

In testimony whereof I affix my signature in presence of two witnesses.

ALBERT W. MEYER.
